UNITED STATES PATENT OFFICE.

GUY B. HUMES, OF CHICAGO, ILLINOIS.

APPLIANCE FOR HORN MUSICAL INSTRUMENTS.

1,350,409.

Specification of Letters Patent. Patented Aug. 24, 1920.

Application filed March 22, 1919. Serial No. 284,265.

To all whom it may concern:

Be it known that I, GUY B. HUMES, a citizen of the United States, and a resident of the city of Chicago, county of Cook, and 5 State of Illinois, have invented certain new and useful Improvements in Appliances for Horn Musical Instruments, of which the following is a specification.

My invention relates to an appliance for 10 horn musical instruments and has for its object the production of an appliance for horn musical instruments which will change some of the clear notes of such an instrument to harsh and indistinct notes, thereby causing 15 a rasping and semi-discordant sound. A further object is the production of an appliance for horn musical instruments which will be easily and readily inserted in the bell of a horn and securely and firmly retained 20 therein.

Other objects will appear hereinafter.

The invention consists in the combinations and arrangements of parts hereinafter described and claimed.

25 The invention will be best understood by reference to the accompanying drawings forming a part of this specification, and in which—

Figure 1, represents a side elevation of 30 the device showing it applied to a musical instrument, and

Fig. 2, is a top plan view of the device, partly in section.

The preferred form of construction, as 35 illustrated in the drawings, consists of a plurality of partially conically shaped tubes 1 which are partially elliptical at their larger end 2 and secured together, as shown, by solder or any other suitable means. Inter- 40 mediate the center of said tubes 1 and their larger or elliptical ends, openings 3 are provided therein, said tubes at said openings having an upwardly projecting annular flange 4. Cylindrical interiorly threaded 45 bands 5, having an inwardly projecting annular flange 6, are secured to each of said tubes 1 by flattening said flange 4 down over said flange 6, thereby securely clamping said member 5 to the member 1. There is thus 50 formed at the base of member 5 a seat 7.

A cylindrical exteriorly threaded ring or band 9 having an inwardly extending annular flange 10 is adapted to be threaded into member 5, thereby affording a means 55 of securely clamping the member 8 between the members 10 and 7. The member 8 is

a circular disk formed from silk, fish skin, oiled paper or the like material to present a membranous vibrator.

Secured to the tube 1, near its smaller end 60 11, are curved metallic spring strips 12, said members 12 being secured to said tube at one extremity only. At both ends of said members 12 are perpendicularly extending studs 13 secured to said members 12 by glue, 65 or any other suitable means. The device is adapted to be inserted into the bell 14 of a horn musical instrument, leaving the members 9 clear or exterior of the horn. The studs 13 are preferably made of felt, cork, 70 rubber, or some other fibrous material which will afford a close engagement with the wall of the horn. The studs 13 will cause the members 12 to be pressed into closer proximity to each other, thereby tending to 75 straighten said members. It is evident that there will be exerted outward pressure on the studs 13, thereby holding the device securely in operative position. The ends 2 of the tubes 1 are sealed air tight, while the 80 opposite ends 11 of said tubes are left open, permitting the free passage of air into said tubes when the horn instrument is used.

By inserting the device into the bell of a horn instrument, the tones are mingled together and combined in such a manner as to produce, through the vibrations of the membranous film, a harsh or grating sound, or what is now popularly termed, a "jazz" sound. Mingling of the notes results in a 85 greater volume of sound and the destruction of the individuality of the different notes. The clear notes proceeding from the instrument are broken up into notes of different wave lengths and a multiplicity of inharmonious notes results. It is evident, from 90 Fig. 1, that some of the clear notes escape from the horn without being acted upon by the device described.

The effect of the device upon the notes is 100 not in the nature of a reed effect, but gives greater volume to the instrument. In case the volume is excessive, one or more of the films may be removed, until the desired effect is obtained. For horn instruments having a larger bell, the device may consist of a 105 larger number of the tubes.

While I have illustrated and described the preferred form of construction for carrying my invention into effect, this is capable of 110 variation and modification without departing from the spirit of the invention. I,

therefore, do not wish to be limited to the precise details of construction set forth, but desire to avail myself of such variations and modifications as come within the scope of the appended claims.

Having described my invention, what I claim as new and desire to secure by Letters Patent is:—

1. In a device of the class described, a plurality of tubes having one end thereof closed and having an opening in each of said tubes intermediate the ends thereof; and a vibrator disposed over said opening, substantially as described.
- 15 2. An appliance for horn musical instruments comprising a plurality of tubes each having one end thereof closed and a lateral opening intermediate the ends; a vibrating element disposed over said lateral opening; and means for securing said vibrating element in its disposed position; and means for securing the device in the bell of a horn musical instrument, substantially as described.
- 25 3. In a device of the class described, a plurality of tubes fastened together at their longitudinal sides, each of said tubes having one end thereof closed and a lateral opening intermediate their ends; an outwardly projecting annular flange secured to each of said tubes at said lateral opening; an annular seat at the base of said flange; a membranous element disposed on said seat over said opening; and means coöperating with said outwardly projecting flange for securing said membranous element on said seat, substantially as described.
- 30 4. In a device of the class described, a plurality of tubes fastened together at their longitudinal sides, each of said tubes having one end thereof closed and a lateral opening intermediate their ends; an outwardly pro-

jecting interiorly threaded annular flange secured to each of said tubes at said lateral opening; an annular seat at the base of said flange; a membranous member disposed on 45 said seat over said opening; and an exteriorly threaded ring having an inwardly projecting flange at one end and adapted to thread into said annular flange, thereby clamping said membranous member to said 50 seat, substantially as described.

5. In an appliance for horn musical instruments, a plurality of tubes secured together having the exterior ends thereof closed and a lateral opening in each tube intermediate its ends; a membranous film disposed over the lateral opening in said tubes; curved spring strips secured at one end to each of said tubes; and means secured to said strips for engaging the interior wall of the 60 musical instrument with which used, substantially as described.

6. In an appliance for horn musical instruments, a plurality of tubes secured together having the exterior ends thereof 65 closed and a lateral opening in each tube intermediate its ends; a membranous film disposed over the lateral opening in said tubes; curved spring strips secured at one end to each of said tubes; and laterally projecting 70 studs on both ends of said strips for engaging the interior wall of the musical instrument with which used, substantially as described.

In testimony whereof I have signed my 75 name to this specification in the presence of two subscribing witnesses.

GUY B. HUMES.
